UNITED STATES PATENT OFFICE

JAMES R. WHITE, OF FLUSHING, NEW YORK, ASSIGNOR TO JENKINS BROS., OF NEW YORK, N. Y., A CORPORATION OF NEW JERSEY

DESIGN FOR A BOX

Application filed October 5, 1932. Serial No. 45,228. Term of patent 14 years.

To all whom it may concern:

Be it known that I, JAMES R. WHITE, a citizen of the United States, residing at Flushing, in the county of Queens and State of New York, have invented a new, original, and ornamental Design for a Box, of which the following is a specification, reference being had to the accompanying drawing, forming part thereof.

The figure is a perspective view of a box showing my new design, in which the top section is cut away in part, the line of severance being along a diagonal of said section, part of the circumference of the circular central figure and the tip of the diagonally disposed arrow.

I claim:

The ornamental design for a box, as shown and described.

JAMES R. WHITE.
